UNITED STATES PATENT OFFICE.

ARTHUR H. HEDLY, OF CHICAGO, ILLINOIS, ASSIGNOR TO THE LUDLOW TYPOGRAPH COMPANY, OF CHICAGO, ILLINOIS, A CORPORATION OF MAINE.

PUNCH FOR MAKING TYPOGRAPH-MATRICES AND THE LIKE.

1,318,381.

Specification of Letters Patent.

Patented Oct. 14, 1919.

Original application filed August 21, 1914, Serial No. 857,868. Divided and this application filed September 30, 1918. Serial No. 256,224.

To all whom it may concern:

Be it known that I, ARTHUR H. HEDLY, a citizen of the United States; and a resident of Chicago, county of Cook, and State of Illinois, have invented a new and useful Improvement in Punches for Making Typograph-Matrices and the like, of which the following is a specification, the principle of the invention being herein explained and 10 the best mode in which I have contemplated applying that principle, so as to distinguish it from other inventions.

The present improvements relate, as indicated, to the manufacture of matrices for typographs and comprise more especially certain features of improvement disclosed in my application filed August 21, 1914, Serial No. 857,868, (since issued into Patent No. 1,237,643, dated August 21, 1917), 15 for manufacture of matrices for typographs, which were required to be divided out of said application. These features refer primarily to the construction of the punch used in forming the intaglio character-impressions in the matrix bars or blanks, the object being to secure a uniform depth of 20 strike throughout the entire extent of the impression, irrespective of variations in width or confirmation of the character.

To the accomplishment of the foregoing and related ends, said invention, then, consisting of the mechanism hereinafter fully described and particularly pointed out in the claims, the annexed drawing and the 25 following description setting forth in detail certain means for carrying out the invention, such disclosed means illustrating, however, but one of various ways in which the principle of the invention may be used.

In said annexed drawing:—

Figure 1 is a vertical sectional view of the bed of a driving press or punching machine equipped with a punch embodying the features of present interest; Fig. 2 is a perspective view of a blank matrix-bar or plate; Fig. 3 is a similar perspective view of such bar after it has been punched; Fig. 4 is a perspective view of the punch; Fig. 5 is a side elevation of a punched bar or 30 blank showing the method of gaging the

strike of the punch; Fig. 6 is a plan view on an enlarged scale of the operative face of a typical punch; Fig. 7 is a developed section of such punch showing the variation, somewhat exaggerated, in the elevation of 55 the raised character thereon; and Figs. 8, 9 and 10 are transverse sections of such raised character taken on the plane indicated by the lines 8—8, 9—9 and 10—10, respectively, on Fig. 6.

The only portions of the general mechanism that require to be described, or even referred to, in the present connection are the bed 1 and the punch head 7, these parts being relatively reciprocable so as to alter- 60 natively advance and retract the punch B with respect to the matrix bar or plate A, shown as held in operative position on the bed 1. The details of the mechanism whereby successive bars A may be brought 65 in position for punching, and there held in the manner illustrated in the figure in question, form no part of the present invention. The same is true of the details of construction of the head 7 whereby the punch B is 70 adjustably supported to vary the depth of the strike as well as to properly locate it with respect to the matrix bar or plate A.

The general form of the punch B employed in driving character-impressions into 80 the blank matrix bars is indicated in Fig. 1, but shown in more detail in Fig. 4. From these figures it will be noted that the lower end b of the punch is formed to enter the recess a in the opposed edge of the matrix 85 bar (see Fig. 2), such recess being a characteristic feature of the particular bars in hand, and it being understood that the face of the punch may be changed in form to suit the kind of matrix bar.

I have found where a character-impression is thus formed by means of a punch instead of by being engraved, that considerable difficulty is encountered in forming an intaglio impression in the metal of the 95 matrix bar, which will be of uniform depth throughout, as is necessary if the raised type character subsequently cast from such impression is to have a perfectly plane printing face. It does not suffice to have the 100

punch face perfectly plane, for I have found that the finer the line being struck, the deeper the impression remains, whereas a relatively wide face on the punch, although impressed to the same depth in the material, will leave a relatively shallower strike. Accordingly, in forming the punch face of a character such, for example, as a capital C (see Fig. 4), I lap off the narrower portions of such character, as indicated in a somewhat exaggerated fashion in the figure in question and in Figs. 7 to 10 inclusive. When such a die is impressed into the material of the blank, while the lapped-off portions do not penetrate as deeply as the broader portion, the result will be an intaglio impression having its bottom in substantially the same plane.

There will, of course, be a different punch 20 for each character, and the body of such punch will correspond in its cross-sectional dimensions with those of the matrix, being just a trifle less, so that the punch may move freely in the well or recess in the bottom of 25 which the matrix blank is held gripped between the chuck jaws. As a matter of fact, as explained before, it is the bed 1 of the machine, with such chuck jaws and matrix blank, that are moved relatively to the 30 punch, rather than vice versa, the range of movement being slight, since it is only necessary to lower the blank sufficiently to allow the punch to clear the recess a in such blank, and thus permit of the insertion of a 35 second blank after the character-impression has been struck in the first.

The upward movement of the bed of the machine carrying the blank, is limited by the engagement of the flat upper faces of 40 the chuck jaws with a plate 60 secured to the under side of the head 7, and forming part of the means whereby the punch is secured to such head.

In order to adjust the depth of the strike, 45 since the bed and the head thus occupy a fixed relation at the end of the punching stroke of the press, it is necessary to provide for the vertical adjustment of the punch. The plate 60, just referred to, is 50 accordingly slidably held in ways 61 in a second plate 62 directly attached to the under side of the head, said ways inclining slightly to the horizontal, as indicated in Fig. 1. The first-named plate 60 is provided 55 with an under-cut slot 63 adapted to receive and slidably hold block 64 to T-shape, to which in turn is attached the punch B by means of a screw 65 passing through the upper end of the same, and the depending 60 portion of such block 64. Obviously if the slidable plate 60 be moved along its supporting ways 61 in the other plate, the punch and its supporting block being held against such movement by reason of the engagement

of the former in the well 17 between the 65 chuck jaws, such punch will be slightly raised or lowered, depending upon the direction of movement of said plate 60.

Such movement is effected by means of a 70 threaded spindle 66 rotatably but longitudinally immovably held in a bracket 67 attached to the front face of the head 7. The outer end of such spindle is provided with a hand-wheel 68 to facilitate its rotation, while the threaded portion thereof engages with an upwardly projecting arm 69 on the plate. By means of such screws and the slight angle of the ways, it will obviously be possible to secure a very fine adjustment of the punch vertically in the well, and thus obtain a strike of exactly the depth desired in the production of any given character impression. By providing a micrometer scale (not shown) in connection with the wheel 68, or other movable part associated with the adjustment of the punch, the correct position of parts for any particular punch, once ascertained, can be readily returned to when the punch is used again, such correct position being empirically determined in the first instance. In other words, the character impression is struck in the blank matrix, and the depth of such impression is then carefully gaged by means of a suitable instrument, and the punch is 95 thereupon adjusted, if necessary, until exactly the right depth has been obtained.

Although reference is thus made to the depth of the character impression, what I actually depend upon in manufacturing 100 matrices with my present improved mechanism, is the distance between the bottom of such impression and the back of the bar. In other words, I have found that it is much more advantageous to measure the drive 105 from the back of the bar instead of from its face. This distance a' (Fig. 5) being preserved accurately, the distance a^2 between the front and back faces of the matrix bars may in turn be measured with reference to 110 the same backs, and thus the depth of the impressions below the plane of such faces be likewise accurately determined. This method of gaging the location or depth of the character impressions in matrices of the 115 kind in hand, has, so far as I am aware, never been attempted before.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In mechanism of the class described, a punch for forming intaglio character-im-

pressions in matrix bars, the face of the relief character on said punch varying in elevation, substantially as and for the purpose set forth.

5 2. In mechanism of the class described, a punch for forming intaglio character-impressions in matrix bars, the relatively nar-

row portions of the relief character on said punch being lapped off so as to be lower than the relatively broad portions of such 10 character.

Signed by me, this 24th day of September, 1918.

ARTHUR H. HEDLY.
